The ornamental design for a transportation safety ring for cylindrical containers, as shown and described.

DESCRIPTION

FIG. 1 is a perspective view of a transportation safety ring embodying the ornamental design of this invention; FIG. 2 is a top plan view of the ring illustrated in FIG. 1;

FIG. 3 is a bottom plan view thereof; FIG. 4 is a front elevation thereof;

FIG. 5 is a side elevation thereof;

FIG. 6 is a rear elevation thereof; and,

FIG. 7 is a cross sectional view taken substantially along vantage line 7—7 of FIG. 1 and looking in the direction of the arrows thereon.

FIG. 1
